BARREL AGITATOR AND HANDLE

Charles E. Farrington, Phoenixville, Pa.

Application March 31, 1933, Serial No. 663,739

9 Claims. (Cl. 259—108)

This invention relates to a novel form of construction of barrel agitator and handle therefor for use in mixing paints or other liquids and to means for holding securely the parts of the agitator in proper position during transportation, storage and use. The device is designed to furnish the user of paint shipped in barrels with proper mechanism for rotation of the stirrer blade member in the form of a handle securely clamped to the barrel head in shipment and detachable for use. It further provides means for rigidly maintaining the agitator in position during shipment and storage. Heavy paint in storage for any considerable period of time settles, the heavy pigment forming a mass in the bottom of the barrel, and if the barrel be stored with the top end down, then when reversed into proper position for stirring and mixing, the heavy mass of pigment which may weigh as much as five hundred pounds may move downwardly and as, under the present practice, the stirrer blade is commonly inserted before the paint is introduced into the barrel and is not secured in any manner at its upper end, the heavy mass may pull the stirrer blade down and away from the bunghole. Further, when the barrel is dropped or otherwise roughly handled the stirrer blade is liable to be shaken or sprung out of its proper position at the bunghole. The form of device hereafter described includes an effectual guard against such displacement. I have also provided a certain and secure means for effective maintenance of the stirrer blade in proper operative position during stirring of the contents of the barrel. This is most essential in proper mixing of paint. The stirrer blade, however, by reason of its shape, often tends to rise during rotation when it encounters heavy masses or lumps of pigment in the paint. By the use of a new form of a handle insertible and removable through a hole in the upper portion of the blade, so devised as to engage with the bunghole walls, the tendency of the blade to climb upwardly in rotation is definitely checked and any vertical movement of the blade is effectively prevented. Thus the operator is enabled to use the agitator or mixing blade to its full advantage.

Fig. 1 is a plan view of the top of a barrel showing a handle and holding means therefor.

Fig. 2 is a vertical cross-section of the barrel with the agitator in place.

Fig. 3 is a section on the line 3—3 of Fig. 1, showing one form of means for securing the agitator blade.

Fig. 4 is a horizontal section on line 4—4 of Fig. 3.

Fig. 5 is a perspective view of the holding clamp for securing the handle to the barrel head.

Fig. 6 shows in cross-section the pivot stud on the bottom of the barrel and a portion of the stirring blade.

Fig. 7 illustrates the first step in inserting the handle in the agitator.

Fig. 8 is a cross-section of the bunghole fitting 10 an upper portion of the blade in the bunghole, the adjacent portion of the handle being shown in position for operation.

Fig. 9 is a cross section of an alternative construction of the device shown in Figure 3.

The same reference characters indicate the same parts in all figures.

The handle 1 is preferably detachably secured to the top of the barrel by means of a washer 2 which has an extension 3 adapted to engage 20 over the central portion of the handle 1 and to clamp the handle against the barrel head. The washer 2 is retained in place by a hexagonal threaded cap 4 which, as shown in the form illustrated in Fig. 3, may be provided with a male 25 thread. In the cap are drilled holes 5 to receive a pin 6. In the use of the invention the pin 6 is the fastening means whereby the blade 7 is retained in position within the bunghole of the barrel during shipment and storage. To this end 30 the pin is inserted through a hole 8 at the upper end portion of the blade 7. Thus, in preparing a barrel of paint or the like for shipment the blade 7 is withdrawn from the barrel sufficiently to permit insertion of the pin 6 through the hole 35 8 and also into the holes 5 drilled in the side of the bunghole cap, whereupon the cap 4 is screwed into a threaded bunghole fitting 11 by means of a wrench applied to the hexagonal head of the cap.

In another form of the invention aligned holes may be drilled through the wall of the bunghole fitting 11' to receive the pin 6 when it is passed through the hole 8 of the blade as shown in Fig. 9. The pin is then retained in this position by 45 means of the bunghole cap 4' which, in this case, is provided with a female thread.

I have provided a form of handle which has proven particularly effective in preventing upward or downward movement of the blade when 50 it is rotated in heavy material. The handle is so formed that it may be inverted for the insertion of its end portion 10 into the hole 8. It is then righted and the projection 10 is engaged under the wall of the bunghole 11, the blade 7 55

- being held between the end portion 10 and an adjacent lateral projection 9. There is thus secured closely fitting rigid engagement of the handle with the blade and with the bunghole wall.
- 5 The blade in operating position thus is held within in the bunghole by the projection 10 of the handle beneath the bunghole wall and is thereby prevented from upward movement during the stirring operation so long as the handle is held in 10 normal stirring position.
- If desired, the nose or entering portion 10 of the handle may be made flattened at its top section in operating position to militate against the rolling of the handle in the hole, thereby helping 15 to keep the crank handle 15 in approximate upright position during operation.
- To permit the blade to be drawn out of the barrel, I prefer to provide an elongated locking stud 12 of suitable length on which is pivoted the 20 bottom portion 14 of the blade 7. The blade may be drawn upwardly to permit the insertion and removal of the locking pin 6, a nut 16 preventing disengagement of the blade from the stud. It will thus be seen that there is provided 25 effective means of retaining the handle readily available without danger of misplacement or loss during shipment so long as the bunghole cap is retained in place. The blade is thus secured in proper place during transit and in storage, and 30 is easily adapted for agitation.
- What I claim is:
1. In combination with a container having a bunghole fitting in its head, a stirring blade extending from adjacent to the bottom of said container up into said bunghole, the upper end portion of said blade having a perforation therethrough, and means for preventing said upper portion of the blade from slipping from the bunghole into the interior of the container, said means 35 including a removable pin extending through said perforated portion of the blade and supported by said fitting.
  2. In combination with a container having a bunghole fitting in its head and a stirring blade 40 therein extending from the bottom thereof into the bunghole, said blade having a hole through each end portion thereof, an elongated pivot stud at the central bottom portion of said container, extending through the hole in the lower end of the blade, a nut on the upper end of said stud 45 permitting limited vertical movement of the blade, the stud being of sufficient length to permit the upper end of the blade to be lifted above the bunghole for the insertion of an operating handle in the hole in its upper portion, and a detachable operating handle having an end portion adapted to be inserted through the upper 50 hole in the blade when the blade is elevated.
  3. In combination, a stirrer blade provided with 55 a hole at the upper portion, a crank handle adapted for insertion into said hole to engage said blade for rotation thereof, said crank handle having a grip portion at one end and a lug at the other end, adapted to engage under the inner end of a bunghole fitting when the handle is in position 60 for operation so shaped so that when said handle grip is pressed downwardly during rotation, upward and downward vertical displacement of the upper portion of the blade is substantially 65 prevented.
  4. In combination, a container, a bunghole fitting in the head thereof projecting downwardly

from the head and threaded for the reception of a cap, the downwardly projecting portion of said fitting being provided with a pair of aligned holes through the walls thereof, a removable pin adapted to extend through said holes and across the bunghole, an agitator blade having an upper portion adapted to be rotated in the bunghole and provided with a hole through which said pin may pass to retain said upper portion in said bunghole.

5. In combination with a container having a removable bunghole fitting in its head, a removable stirring blade consisting of a strip of bar stock having its upper and lower ends in line with the central axis of the container and its 15 intermediate portion bent away to be offset from said axis, and easily accessible and removable means in said removable fitting for retaining the upper end of said blade in the bunghole when the bunghole is closed, said means being operative 20 to prevent vertical displacement of the stirrer blade relatively to said bunghole fitting.

6. In combination, a container having a bunghole in its head, a removable closure fitting for said bunghole, a stirring blade extending from 25 adjacent to the bottom of said container upwardly into said bunghole, the upper portion of said blade having a perforation therethrough, and means carried by said removable closure fitting and extending through said perforated 30 portion of the stirrer blade for retaining the upper portion of the blade within the bunghole, said means being operative to lift the blade upwardly through said bunghole upon removal of the fitting from the bunghole.

35 7. A combination as defined in claim 6 wherein the said means includes a removable pin extending transversely of the closure fitting to which the perforated portion of the stirrer blade is adapted to be loosely connected both when the 40 closure fitting is in position within the bunghole as well as when it is removed therefrom.

8. In combination, a container having a bunghole in its head, a removable closure fitting for said bunghole, a stirring blade disposed interiorly 45 of the container and arranged with its upper end projecting upwardly into said bunghole, and co-acting means in said upper end of the blade and in said closure fitting for effecting the raising of said stirrer blade upwardly through said bunghole upon removal of the closure fitting from the bunghole, thereby rendering the upper end of the blade accessible for the application of an operating tool thereto.

50 9. In combination, a container having a bunghole in its head, a stirring blade disposed interiorly of the container and arranged with its upper end projecting upwardly into said bunghole, said upper end of the stirrer blade having a perforation therein and being normally disposed with the 55 perforation thereof accessible for the application of an operating tool thereto, and an operating tool in the form of a crank handle having a notched enlargement adapted for disposition within the bunghole, said notched enlargement being projected through the said perforation in the stirrer blade with the notch thereof so related to the said perforation that the stirrer blade is restrained against lateral or vertical displacement relatively to said crank handle.
